ELECTRICAL DISCHARGE DEVICE

Edmund Germer, Berlin-Wannsee, Germany

Application April 13, 1937, Serial No. 136,539
In Germany February 22, 1936

7 Claims. (Cl. 176—122)

This invention relates to gaseous discharge devices. More particularly the invention relates to such devices in which the discharge carries a heavy current loading so that a large amount of heat is generated in the discharge.

Prior to my invention there have come into commercial use high pressure vapor discharge lamps of the type described and claimed in my prior copending application, Serial No. 500,346, filed December 5, 1930, and in the use of such devices under various conditions met with in practical use difficulty has been experienced due to the intense loading of the arc and to intense localization of the heating from the arc which occurs under certain conditions of convection.

It is an object of my present invention to provide such a discharge device in which injury to the envelope will be avoided even if the wall of the envelope is made of glass which would be injured by the localized heating of the discharge in the high pressure arc lamp now in use.

According to my invention the parts of the envelope wall which are subjected to localized heating are designed to provide increased heat dissipation, e. g., by convection, radiation, etc.

In the accompanying drawing, I have shown several embodiments of my invention and below I have suggested various modifications thereof. It should be understood, however, that these are not intended to be exhaustive or limiting of the invention, but on the contrary are given in order that others skilled in the art may fully understand the invention and the principles thereof so that they may be able to adapt it and modify it and to embody it in numerous other forms each as may be best adapted to the particular conditions and requirements of any intended use.

In the drawing:

Fig. 1 shows, partly in elevation and partly in section, a lamp suitable for commercial use which embodies my invention;

Fig. 2 is a cross sectional view taken on line 2—2 of Fig. 1;

Fig. 3 is a cross section taken on line 3—3 of Fig. 1;

Fig. 4 is a view in side elevation of a lamp designed for horizontal burning;

Fig. 5 is a cross sectional view of a lamp similar to that shown in Fig. 4, but of modified shape; and

Fig. 6 is a cross sectional view of another lamp intended for horizontal burning.

Referring first to Fig. 1, I have shown there a lamp similar to the high pressure mercury vapor lamps which are now in common use, in that

there is an inner envelope 10 provided with electrodes (not shown) at opposite ends mounted on lead-in wires 11 and 12 sealed through the ends of the envelope 10. Around this envelope, in order to protect it from unregulated convection currents or draughts, is the jacket 13 of glass or other light permeable material; and to one end of this jacket is cemented a connector base 14, e. g., of the ordinary Ediswan Mogul type. A resilient frame 15 is mounted within the jacket 10 13 to hold the envelope 10 in place and serves also to conduct the current for the arc to the farther lead-in wire 12.

To this extent the lamp is similar to others which are now in use. The form of the envelope 15 10, however, and the form of the frame 15 are improved in the construction shown in this drawing as compared with similar lamps known prior to my invention. The frame is more fully described and claimed in a co-pending application 20 of F. H. A. Brandt.

In the upper part of the envelope 10 I have provided corrugations 16 which increase gradually in depth from near the middle of the tube to its upper end. The jacket 13 is filled with a convection gas, e. g., atmospheric air at approximately 1 atmosphere pressure, and these corrugations 16 provide channels in which the convection currents flow smoothly and rapidly in contact with the glass. Thus in the upper portion 30 of the envelope where the convection currents within the envelope tend to concentrate the heat from the arc the heat dissipating capacity of the envelope is correspondingly increased.

It is advantageous to form the corrugations as shown, for example, in Fig. 2, with the extended folds narrower than the re-entrant folds. Thus the part of the folded wall which is nearest to the center of the tube is exposed to a convection stream sufficiently broad to keep these portions 40 cooled. The outwardly extended folds, however, must not be so narrow as to allow excessive cooling of their outermost parts which would cause condensation of the metal vapor when such is used within the tube.

A similar desirable effect can be obtained by corrugations extending transversely around the tube instead of longitudinally. Where the lamp is to be burned in vertical position, however, this is not to be recommended because the parts most 50 strongly heated on the interior are least exposed to the convection currents on the exterior. When, however, the tube is to be burned in horizontal position, such transverse corrugations are advantageous for the same reason. In such case, 55

however, it is not necessary or desirable to have the corrugations extend completely around the tube, but on the contrary they are preferably extended with gradually increasing depth from 5 about the middle of the tube to the top. This I have shown, for example, in Fig. 4, in which corrugations of increasing depth are provided beginning near the ends in which transverse corrugations of this type are provided beginning 10 near the ends and increasing respectively in depth to the center of the tube where the upper wall is most strongly heated due to the upward curve of the arc between the electrodes.

In Fig. 5, I have shown in cross section a tube of 15 particularly advantageous form. In this case the tube is streamlined in cross section. This has two-fold advantage. In the first place, the streamline permits the convection currents to flow more rapidly and smoothly in contact with the 20 glass of the tube and thus, makes for increased heat-exchange efficiency. In the second place, the departure from the circular form increases the area in which the inner and outer gases are in convection contact with the wall. Another ad- 25 vantage is that the gradual increase in the upward extension of the tube wall toward the center of its length, carries it above the arc path which would be necessary in a simple cylindrical tube.

In Fig. 6, I have shown in cross section a 30 streamlined tube which attains advantages of streamlining, but without the increased area due to corrugations.

This application is a continuation in part of 35 my application Serial No. 119,405, filed December 24, 1936, for Electrical discharge devices.

What I claim is:

1. A gaseous electrical discharge device comprising spaced arcing electrodes, an envelope closely surrounding a discharge path between the 40 electrodes, a material within the envelope adapted to provide a gaseous atmosphere for the discharge, and a cooling fluid outside said envelope which is characterized by the envelope having upwardly directed channels near its top for flow of con- 45 vention gases and giving it a greater average convection area per unit length near its top than near its bottom, whereby to counteract by increased cooling the tendency of convection in the discharge carrying gas to concentrate heat from the discharge in the upper part of the envelope.
- 50 2. A horizontal burning high pressure arc burner of the type having spaced arcing electrodes, an envelope closely surrounding an arc path between them, a material within the envelope adapted to provide an atmosphere for the

arc of pressure sufficient to give it the form of a luminous cord constricted away from the wall of the envelope which is characterized by the upper part of the envelope being transversely corrugated at least in the portion between the electrodes 5 where the arc tends to approach said upper part.

3. A horizontal burning high pressure arc dis- 10 charge device as defined in claim 2 in which the envelope at least at the top of the corrugations is stream-lined in cross-sectional shape taken par- 10 allel to the corrugations.

4. A horizontal burning high pressure arc burner of the type having spaced arcing electrodes, an envelope closely surrounding an arc path be- 15 tween them, a material within the envelope adapted to provide an atmosphere for the arc 20 sufficient to give it the form of a luminous cord constricted away from the wall of the envelope which is characterized by the envelope being streamlined in cross sectional shape and exposed 20 to a convection fluid whereby the upper part of said convection surface is in more efficient heat- 25 exchange contact with the convection gas than the corresponding part of a circular tube of equal cross sectional area.

5. A high pressure arc burner of the type hav- 30 ing spaced arcing electrodes, an envelope closely surrounding an arc path between them, a mate- 35 rial within the envelope adapted to provide an atmosphere for the arc of pressure sufficient to give it the form of a luminous cord constricted away from the wall of the envelope which is char- 40 acterized by the upper part of the envelope being corrugated.

6. A high pressure arc discharge device as de- 45 fined in claim 5, in which the envelope at least at the top of the corrugations is streamlined in sec- 50 tional shape taken parallel to the corrugations.

7. A high pressure arc burner of the type hav- 40 ing spaced arcing electrodes, an envelope closely 45 surrounding an arc path between them, a material within the envelope adapted to provide an atmos- 50 phere for the arc of pressure sufficient to give it the form of a luminous cord constricted away from the wall of the envelope which is character- 55 ized by the envelope being streamlined in sectional shape taken parallel to the convection currents and exposed to a convection fluid in the direction of said streamlining, whereby the upper part of said convection surface is in more efficient heat- 60 exchange contact with the convection gas than would be the corresponding part of a spherical tube of equal cross sectional area.
